United States Patent Office

Des. 221,863
Patented Sept. 14, 1971

221,863

TAPE CASSETTE OR SIMILAR ARTICLE

Lewis W. Bennett, Rochester, N.Y., assignor to
The Singer Company

Filed Apr. 13, 1970, Ser. No. 22,377

Term of patent 14 years

Int. Cl. D14—02; D16—99
U.S. Cl. D26—14

FIG. 1

FIG. 2

FIG. 3

FIG. 5

FIG. 4

FIG. 6

FIG. 1 is a top perspective view of the tape cassette or similar article embodying my new design;

FIG. 2 is a bottom plan of the cassette;

FIG. 3 is a right-hand side view;

FIG. 4 is a left-hand side view;

FIG. 5 is a front view; and

FIG. 6 is a rear view.

I claim:

The ornamental design for a tape cassette or similar article, substantially as shown.
